UNITED STATES PATENT OFFICE.

WALTER E. LE ROY, OF CINCINNATI, OHIO, ASSIGNOR TO UNION SPECIAL MACHINE COMPANY, OF CHICAGO, ILLINOIS, A CORPORATION OF ILLINOIS.

WAISTBAND FOR TROUSERS.

Application filed January 5, 1925. Serial No. 579.

The invention relates to new and useful improvements in trousers, and more particularly to the waist band construction therefor.

- 5 An object of the invention is to provide a waist band construction which includes a stiffening strip and a facing strip, which facing strip is formed in two sections, an upper and a lower section, and wherein the stiffening strip and both sections of the facing strip are secured together by two lines of 60 stitches which are so formed in the sections as to be concealed from view at the front of the garment, when the waist band is attached 10 thereto, by the body fabric of the garment, and concealed from view on the inside of the 15 garment by the facing strip.

In the drawings, which show by way of 20 illustration one embodiment of the invention:

Figure 1 is a sectional view through the body fabric of the trousers, the stiffening strip and the sectional facing strip, the parts of which have been united by the improved 25 arrangement of concealed stitches and prior to the folding of the waist band inside of the garment;

Fig. 2 is a similar view, but showing the 30 waist band structure folded inside of the body fabric of the trousers; and

Fig. 3 is a plan view from the inside of the garment, the several layers being broken away to better show the construction of the 35 waist band.

The invention is directed broadly to a 40 waist band construction wherein a stiffening strip, such as canvas or the like, is secured to a facing strip and to the body fabric of the trousers by concealed stitches. The

45 facing strip is formed in two sections, an upper section and a lower section. The upper section has its edges inturned, and the stitches for uniting the parts pass through these inturned edges of the facing strip only.

The lower section is formed from a strip of 50 fabric folded intermediate its edges and with the edges of the fabric placed between the inturned lower edge of the facing strip and the stiffening strip, and is secured by

55 the concealed stitches which pass through the parts. The body fabric extends over the stiffening strip and down between the stiffening strip and the inturned edge of the upper section of the facing strip and is secured to the waist band structure by the

concealed stitches which pass through this inturned upper edge of the facing strip. When the waist band is turned inside of the trousers, the stitches referred to above are concealed from view at the front of the garment by the body fabric thereof. The stitches are concealed from view on the inside of the garment by the facing strip. 60

In the drawings, the body fabric of the trousers is indicated at 2. The stiffening 65 strip is indicated at 1. This stiffening strip is preferably made of canvas and lies flat in the waist band structure.

The facing strip or skirt consists of an upper section 3 and a lower section 4. The 70 upper section 3 has its side edge inturned at 5 and its lower edge inturned at 6. The body fabric at its upper edge 7 is placed against the inner face of the stiffening strip 1. The inturned edge portion 5 of the facing 75 strip is superposed upon this portion 7 of the body fabric.

The line of concealed stitches 8 is passed through the inturned portion 5 of the facing strip. The thread from which the loops 80 of the concealed stitches are formed lies between the inturned portion 5 and the body portion of the facing strip 3 so that the said thread is concealed from view on the inside of the garment. The loops in this line of 85 stitches are passed through the inturned section 5 of the facing strip, then through the body portion of the trousers, and finally through the upper edge of the stiffening strip, and said loops may be enchainable on 90 the outer face of the stiffening strip or locked by a thread in the ordinary way.

The lower section 4 of the facing strip is folded intermediate its side edges at 9, and the side edges 10—10 are placed together and are superposed upon the lower edge of the stiffening strip 1. The inturned edge 6 of the upper section 3 of the skirt is superposed upon the edges of the folded facing section 4, and concealed stitches 11 are used 95 for securing the parts together. The thread from which the loops of the stitches are formed lies between the inturned portion 6 of the facing strip and the body portion thereof and are passed first through this inturned portion, then through the folded fabric forming the lower section 4 of the skirt or facing strip, and then through the lower edge of the stiffening strip. These loops are secured 100 by being interlocked with each other, or in. 110

terlocked with the usual thread or thread loops.

From the above, it will be apparent that a waist band structure is provided wherein the 5 stitches for securing the parts of the waist band structure are concealed both from the outer face of the garment and the inner face of the garment. These lines of stitches are simultaneously formed. The machine for accomplishing this result is shown in a copending 10 application Serial No. 570 filed of even date herewith.

It will be noted that the lower section of the skirt projects below the edge of the can- 15 vas strip, and this makes a very neat finish for the waist band structure. This lower section may be tacked to the body fabric, if desired, to hold the waist band inside of the trousers.

20 It is obvious that minor changes in the arrangement of the parts may be made without departing from the spirit of the invention as set forth in the appended claim.

What is claimed as new is:

25 The combination with the body fabric of trousers, of a stiffening strip at the waist band of the trousers, said body fabric being folded over the upper edge of said stiffening strip, a skirt comprising upper and low-

er sections, the upper section including a 30 facing strip having its upper edge inturned and placed against the inner face of the folded-over edge of the body fabric, a line of stitching passing through the inturned portion only of the facing strip, said folded-over edge of the body fabric and the stiffening strip and concealed from view at the outer face of the garment by the body fabric and at the inner face of the garment by said facing strip, said facing strip at its lower 40 edge being inturned, the lower section of said skirt comprising a fabric strip folded intermediate its edges with the fold in the fabric at the lower side thereof, and the two edge portions of the folded strip located between the inturned portion of the facing strip and the stiffening strip, a line of stitches passing through said inturned portion only of the facing strip, the upper edges of the folded strip forming the lower section of the skirt, and through the stiffening strip, said last-named line of stitching being concealed from view at the outer face of the garment by the body fabric, and at the inner face of the garment by said facing 55 strip.

In testimony whereof, I affix my signature.
WALTER E. LE ROY.
